(57) **CLAIM**

The ornamental design for a suture anchor device, as shown and described.

DESCRIPTION

FIG. 1 is a perspective view of a new design for a suture anchor device;

FIG. 2 is a second perspective view thereof;

FIG. 3 is a front side view thereof, the rear side view thereof being identical in appearance;

FIG. 4 is a right side view thereof, the left side view thereof being identical in appearance;

FIG. 5 is a top view thereof; and,

FIG. 6 is a bottom view thereof.

The broken line showing portion of a suture anchor device is included for illustrating environmental structure and forms no part of the claimed design.
